UNITED STATES PATENT OFFICE.

ROBERT THOMAS JENNEY, OF LONDON, ENGLAND, ASSIGNOR TO THE LAMSON CONSOLIDATED STORE SERVICE COMPANY, OF NEWARK, NEW JERSEY.

DESIGN FOR A RECEIVING-TUBE FOR PNEUMATIC-DESPATCH SYSTEMS.

SPECIFICATION forming part of Design No. 38,548, dated November 13, 1900.

Application filed August 13, 1900. Serial No. 26,793. Term of patent 14 years.

To all whom it may concern:

Be it known that I, ROBERT THOMAS JENNEY, a citizen of the United States, residing at London, England, have invented and produced a new and original Design for a Receiving-Tube for Pneumatic-Despatch Systems, of which the following is a specification, reference being had to the accompanying drawings, forming part thereof.

Figure 1 is a side elevation of the tube of my new design, and Fig. 2 is an end or front view of the tube.

The leading features of my design comprise a receiving-tube for pneumatic-despatch systems having a straight portion, a curved portion at one end thereof, and a head portion at the other end thereof. Thus in the drawings there is a straight portion 1 of the tube, and

extending from one end is a curved portion 2, having a recess 3 and a closed end 4, and at the other end there is a head portion 5. The curved portion and the head portion are ornamented with open-work, and the straight portion is plain.

What I claim is—

The design for a receiving-tube for pneumatic - despatch systems, substantially as shown as described.

In testimony whereof I have hereunto set my hand in the presence of two subscribing witnesses.

ROBERT THOMAS JENNEY.

Witnesses:

EDWARD TRUMP FOSTER,
ALLEN PARRY JONES.
